METHOD OF AND APPARATUS FOR MEASURING AND RECORDING GAS INTERCHANGEABILITY

Edwin X. Schmidt, Nashota, Wis., assignor to Cutler-Hammer, Inc., Milwaukee, Wis., a corporation of Delaware

Application April 24, 1944, Serial No. 532,434

16 Claims. (Cl. 73—190)

This invention relates to improvements in methods of and apparatus for measuring and recording gas interchangeability.

With respect to gas interchangeability, it may be pointed out that two gases which would be entirely or completely interchangeable would have physical and chemical characteristics such that interchange or substitution one for the other on any gas burning appliance would in nowise change or affect the performance of the gas burning appliance. Such an ideal condition will seldom be obtainable, due to the large number of variable factors affecting combustion, the various uses made of the results of combustion, and the varying effects of the properties of gases on different types of burners.

For a practical consideration of the gas interchangeability problem, it must be appreciated that complete interchangeability is not attainable, and the substitution of one gas or gases for another must necessarily be a compromise; the extent of such compromise depending upon the types of gases involved; and the criterion of interchangeability being somewhat arbitrary in nature, unless the specific type of gas-burning equipment involved and the combustion requirements are known.

In the general distribution of gas to communities, such as in city gas distribution systems, there are certain general combustion characteristic requirements which determine whether consumer appliances will function in a satisfactory manner. The principal properties which affect or control satisfactory performance might be individually measured and determined. As the result of extensive experiments I have found that such properties are: total heating value per standard cubic foot of the particular gas, the density thereof, the percentage value of primary air required to produce a fixed ignition velocity, and the relative volume of primary air-gas mixture producing such ignition velocity when the volume of gas in said mixture is determined by a fixed pressure drop across a fixed restriction. For interchangeability on domestic appliances other combustion characteristics are of much less importance.

These more important properties of a gas can be combined into a single factor, or property of a gas, which I will herein characterize as the interchangeability factor K . To provide for assignment of this factor K to any gas without relating the factor to a second gas, the property of "relative volume of primary air" is, in the value K , related to a type of gas of known charac-

teristics as a basic gas, so that gases of substantially identical K values will produce satisfactory combustion on average domestic consumer appliances.

5 A primary object of the present invention is to provide a method of and apparatus for indicating and/or recording this interchangeability factor or property of a gas.

Another object is to provide for calibration of 10 the device in some standardized scale which may be graduated in numbers which are of significance.

Another object is to provide means enabling 15 adjustment of the device to meet the requirements of each particular installation.

Another object is to provide simple means affording adjustment of the range coverage of the device to suit the requirements of a given installation.

20 Other objects and advantages of the invention will hereinafter appear.

The accompanying drawings illustrate certain 25 embodiments of my invention which will now be described, it being understood that the embodiments illustrated are susceptible of modification in respect of certain structural details thereof without departing from the scope of the appended claims.

In the drawings, 30 Figure 1 is a view, partly in elevation and partly in vertical section, of a gas interchangeability measuring device constructed in accordance with my invention; certain of the parts to provide for recording of the ascertained value being also illustrated.

35 Fig. 2 is a sectional view, on the line 2—2 of Fig. 1.

Fig. 3 is a fragmentary sectional view of a 40 burner tip like that shown in Fig. 1, but illustrating a modified form of probe for cooperation with the inner cone of the burner flame.

Fig. 4 is a front elevational view of one form of recorder which may be utilized in conjunction with the device of Fig. 1, and

45 Fig. 5 illustrates schematically and diagrammatically a system, embodying a modified form of the device of Fig. 1, to afford distant indication and recordation of the aforementioned interchangeability characteristics K of a gas; it being understood that the burner parts not illustrated in Fig. 5 may be identical with those shown in Fig. 1.

It may be pointed out that most domestic appliances, like the burner shown in Fig. 1, have an inherent rate of gas flow depending upon the

pressure across the jet, the size of the jet, and the density of the gas. Thus, the relative rate of gas flow may be expressed as $1/\sqrt{d}$, where d is the density of the gas. The momentum of the gas, which tends to induce a flow of air, is independent of the composition of the gas; depending only upon the gas pressure, and the size and efficiency of the jet. Inasmuch as the jet efficiency does not change appreciably with change in gas composition, and inasmuch as most of the momentum of the gas is transmitted to the gas and primary air and dissipated in the primary air chutes, burners of this type will induce substantially the same amount of air regardless of the gas composition; which fact has been substantiated by numerous tests.

The amount of air required for complete combustion of the gas passing through the jet is dependent upon the rate of gas flow, the heating value per unit volume of the gas, and the quantity of air required per unit of heat in the particular gas. The theoretical required rate of flow of air may thus be defined as $(Hd^a = 1/\sqrt{d})$ (heating value) (a); where d is the density, heating value is in B. t. u. per standard cubic foot, and a is the quantity of air required per B. t. u.

It is a well known fact that domestic gas burning appliances are almost invariably adjusted so that the induced primary air is of a value lower than 100 per cent. In fact most domestic appliances are so adjusted that the percentage of primary air is at a value which produces an ignition velocity substantially lower than the value of primary air which will produce the so-called maximum ignition velocity of the particular gas. Thus most burners with an increase in the percentage value of primary air will produce a higher ignition velocity and an inner cone of smaller size. Moreover, in practice the burners are usually adjusted for a percentage value of primary air which produces approximately the same ignition velocity regardless of the type of gas on which the burner is being operated when the adjustment is made. The result is that on burners supplied with so-called fast burning gases the usual practice is to lower the percentage of primary air and to increase the percentage of primary air for slow burning gases, so that inner cone sizes will be about the same. This fact is important in respect of the matter of gas interchangeability, for it is an inherent characteristic of gases that, within this normal range of burner adjustment, a fixed increment in the percentage value of primary air changes the ignition velocity by a fixed percentage change for most gases; so that gases which are interchangeable in respect of inner cone size with one particular burner adjustment will also be interchangeable for another particular adjustment within the normal range of burner adjustment as used in common practice.

For any one gas the percentage value of primary air which will produce a fixed ignition velocity (which velocity should preferably be a value commonly obtained in domestic appliances) is fixed or constant. For example, to obtain an ignition velocity of 8% of the maximum ignition velocity of hydrogen, the percentage value of primary air for hydrogen is 13%; for propane it is 65%; and for methane it is 76%.

On a burner as commonly adjusted the percentage value of primary air will thus approximately correspond with the percentage value of primary air required for the particular gas. The flow of primary air into the burner may then be

determined from the theoretical air requirement of the particular gas for which the burner was adjusted; namely, the value (Hd^a) (a). For example, with a 580 B. t. u. gas of .59 density, the amount of air required per B. t. u. is .0089 cubic foot. The theoretical relative air requirement would be: $(580/\sqrt{.59})(.0089)$; and if this gas required 56% air for 8% ignition velocity the primary air flow in the burner may be taken as: .56 $(580/\sqrt{.59})(.0089)$.

If another or substitute gas is then supplied to the same burner the rate of primary air flow will remain substantially the same; and in order to again obtain the same 8% of ignition velocity the relative theoretical air requirement of the substitute gas must be such that the percentage value of primary air supplied with the new gas will correspond to the percentage value of primary air required for the new gas to provide 8% ignition velocity.

Propane and air may be mixed to form a gas having these characteristics. Thus, propane and air can be mixed to form a gas in which the quantity of the air flow divided by the relative theoretical air requirement, and multiplied by 100 gives the percentage value of primary air required to produce an ignition velocity of 8%; and a propane-air mixture of this composition would produce the same ignition velocity as was produced by the gas for which the burner was originally adjusted. This propane-air mixture would not necessarily produce the same size inner cone, or same flame stability, for both are determined by the ignition velocity and the velocity of the primary air-gas mixture issuing from the burner port. The latter velocity is not necessarily the same for the propane-air mixture (producing the same ignition velocity as the gas for which the burner was adjusted) as it is for such other gas.

In the example aforementioned the port velocity would be lower on the propane-air mixture due to the higher density of the gas. It will be apparent to those skilled in the art that by mixing propane-air to provide a gas of a slightly higher heating value than that required for establishing the same ignition velocity in the primary mix, the ignition velocity will be reduced appreciably, a phenomenon accomplished by only a slight decrease in port velocity. The decrease in ignition velocity is appreciably larger than the decrease in port velocity, so that by an increase in propane-air heating value from that necessary to obtain the same ignition velocity of the primary air-gas mix as that of the air-gas mix for which the burner was adjusted, a new slower ignition velocity which will produce the same size inner cone and the same flame stability can be obtained. The amount of decrease in propane-air heating value necessary to obtain this result can be accurately determined.

The aforementioned value of K for the gas for which this burner was originally adjusted would then be the relative value of primary air required for this last mentioned propane-air mixture (which would be equal to the percentage value of primary air required for 8% ignition velocity) multiplied by the heating value per standard cubic foot, divided by the square root of the density, and multiplied by the air requirement per B. t. u.

Gases of like K values will then be interchangeable on domestic appliances in accordance with common procedure and will produce similar stable flames. This value of K is used in the

calibration of the instrument herein disclosed and provides a means for calibration and design. In this instrument for indicating gas interchangeability I employ the principle of establishing a flame with a fixed size of inner cone, the size and shape of the inner cone being selected in accordance with the value of K in such a manner that the burner normally will operate with a primary air mixture which will produce an ignition velocity corresponding to that generally used on domestic appliances. The height of the inner cone is used as a criterion.

Referring more particularly to that form of my invention illustrated in Figs. 1, 2, and 4, the numeral 10 (Fig. 1) designates a burner of the Bunsen type, the tube 11 thereof being formed of a suitable metal, such as stainless steel; the upper end portion of said tube being spun inwardly or otherwise shaped as shown at 12 to provide an opening of reduced size to slidably receive an upwardly inserted tubular metal member 13 also preferably formed of stainless steel. Member 13, which serves as the burner tip, has an outwardly extending peripheral flange 14 formed at its lower end to underlie the inner periphery of portion 12 of tube 11; said tubes 13 and 11 being soldered or otherwise rigidly and permanently connected with each other, as indicated at 15. The base 16 of the burner preferably consists of a cast and/or machined member of a suitable metal, such as steel. Member 16 is formed at 17 to provide a seat for the lower edge of tube 11 and to extend telescopically a short distance into the lower end of the latter; said parts being soldered or otherwise rigidly and permanently connected to each other, as indicated at 18.

Base member 16 has formed in the upper end portion thereof a relatively large cavity 19 which serves as a mixing chamber for the primary air and gas supplied to the burner. A circular opening 20 in the bottom wall of cavity 19 opens downwardly to a cylindrical recess 21; base 16 having an outwardly extending flange 22 peripherally surrounding the lower portion of recess 21. Flange 22 is provided with a multiplicity of openings to freely accommodate the shanks of screws 23, which shanks take into a corresponding number of tapped openings provided in a support plate 24, which is soldered, welded or otherwise rigidly attached to the walls of a housing the illustrated fragment of which is designated by numeral 25. A bracket 26 is attached to one wall of housing 25 and to plate 24 to assist in supporting the latter.

Slidably mounted upon the tubular connecting portion 27 of an expansible bellows type thermally responsive unit is a hollow bushing 28 internally threaded at 29, an externally threaded gland 30 having a polygonal head 31, and a quantity of suitable packing material 32. Bushing 28 is provided at its lower end with an annular flange 33 which underlies the flange 22; flange 33 having clearance openings for, and flange 22 having tapped recesses to accommodate, the shanks of a multiplicity of clamping screws 34; a gasket 35 of rubber or rubber-like material being interposed between flanges 22 and 33 to render such connection gas- and air-tight. When tubular portion 27 has been properly positioned with respect to bushing 28 (as hereinafter described), gland 30 may be driven inwardly to compress or compact the material 32 to clamp said parts in such assembled position and to likewise render the connection therebetween gas- and air-tight.

The upper end of tubular portion 27 extends upwardly for a substantial distance through an opening of corresponding size in the lower end of a substantially cylindrical container 36, as shown at 37; said parts being soldered or otherwise secured to each other as shown at 38 to provide a liquid-tight and pressure-resisting connection therebetween. The upper end wall 39 of container 36 is preferably of approximately cone-shape; the same having a central opening therein to closely accommodate the lower end portion of a metal member 40 of circular form in transverse cross section. Said lower end portion extends downwardly into container 36 to a point rather closely adjacent the end 37 of tubular portion 27; said lower end portion being drilled or otherwise formed with a recess 41 opening to the lower end thereof; the peripheral wall of recess 41 at the upper end thereof having one or more openings 42 formed therein within container 36 to afford direct communication between the upper end of recess 41 and the upper end portion of container 36. Wall 39 is soldered or otherwise rigidly secured to member 40 as shown at 43 to provide a liquid-tight connection between these parts.

Member 40 is provided at its upper end with a reduced portion in the form of a threaded extension or stud 44 over which a central (threaded or clearance) opening in a spider or spacer 45 (Figs. 1 and 2) is adapted to fit. A metal probe 46, the lower end portion of which has the same diameter as member 40, has formed therein a tapped recess 47 to accommodate stud 44, whereby probe 46 and spider 45 may be rigidly but removably secured to member 40. As best illustrated in Fig. 2, spider 45 fits closely within the tubular member 13 to center and stabilize the parts against transverse movement relatively to burner 11 or the member 13 thereof. As shown at 48 probe 46 is preferably provided with a curved tapering contour from a given point to the upper end thereof; said upper end having only a slight radius of, say, one-sixteenth of an inch or less.

The parts thus far described will be assembled in such a manner that the tip or upper end 48 of probe 46 will project upwardly a predetermined distance beyond the upper edge of burner tip 13; such distance being selected in accordance with the contemplated height of the inner cone 49 of a flame 50 to be produced by a gas to be normally supplied to the device. As aforesaid, it is preferred that the tip of probe 46 shall be so located that it is just at the center of the surface or area which defines the inner cone 49 of the flame. Under these conditions a more or less constant quantity of heat will be transmitted by radiation from the inner cone of the flame to probe 46, the effect of the heat so transmitted being normally neutralized or balanced, with respect to the liquid 51 within container 36, by the flowing mixture of primary air and gas upwardly through burner 11 to the point of combustion at the burner tip 13; as hereinafter more fully described.

The aforementioned tubular connecting portion 27 communicates at its lower end with the interior of an expansible and contractible bellows, which is shown at 52 as having corrugations in the vertical peripheral wall thereof. Bellows 52 has its lower end wall soldered, brazed or otherwise rigidly secured to the bottom wall of a cup-shaped housing member 53, as shown at 54; said housing member having an externally threaded nip-

ple 55 formed thereon. Nipple 55 has a central opening, formed by a reentrant flange 56, to accommodate said tubular portion 27; the latter being soldered or otherwise rigidly secured to nipple 55 as indicated at 57.

Nipple 55 extends downwardly through a suitable opening in the horizontal portion of a bracket member 58, one vertical arm 59 of which is secured to an inwardly offset vertical wall portion 60 of housing 25, as by means of a screw 61; the other vertical arm 62 of bracket 58 being secured by a pair of screws 61 to the opposite inwardly offset vertical wall portion 63 of housing 25. Arm 62 of said bracket is provided at its upper end with an inwardly extending horizontal portion 64, to which a cantilever type spring 65 and another bracket member 66 are attached, as by means of a pair of screws 67. The use of spring 65 provides an important advantage over the conventional type of pivot, in that it affords a frictionless oscillatable connection, and a fixed relationship is thereby insured between the axis of the valve member 83 and the valve seat or opening 87 hereinafter described.

Spring 65 has rigidly and permanently attached to the free end portion thereof, as by means of a plurality of rivets 68, a sheet metal lever member 69, between which and an upwardly offset portion 70 of bracket 66 a coiled compression spring 71 is interposed. Spring 71 serves to load lever 69 and to yieldably resist upward displacement thereof as an incident to expansion of bellows 52 by the effect of heat upon the liquid 51 within the latter. For this purpose bellows 52 has attached to the upper end thereof a disk or plate 72 carrying centrally thereof a stud or pin 73, the cone-shaped upper end 74 of which is adapted to bear within a recess (not shown) formed in the lower surface of a metal member 75 carried by lever 69.

A nut 76 which is captive upon the aforementioned tubular portion 27 is adapted to cooperate with nipple 55 to clamp the aforementioned housing member 53 to bracket member 58. Attached to the upper end of member 53 is a metal cover plate 77; the latter having a central opening to provide operating clearance for stud 73, and said cover plate preferably having a downwardly extending circular rib 78 formed thereon for cooperation with plate 72 to limit the maximum degree of upward movement of stud 73.

Lever 69 has formed integrally therewith an upstanding lug 79, to which a relatively long pointer 80 may be attached at the point and at the angle indicated, as by means of rivets 81. Pointer 80 is adapted to cooperate with a suitable stationary scale 82 which may be calibrated in any suitable or desired manner to afford an instantaneous and continuous indication of the interchangeability characteristics of the gas supplied to the device; as, for instance, by applying percentage values of 10 to 50 per cent on each side of the intermediate or zero value illustrated.

Removably attached to the right-hand end of lever 69 is a movable valve member 83 which is preferably in the shape of a frustum of a cone; said valve member having a threaded stud 84 extending downwardly through a suitable opening in lever 69 for cooperative engagement by a clamping nut 85. The stationary portion of the valve comprises a cup-shaped metal member 86 having a centrally located circular opening 87 formed in the bottom wall thereof; said opening having a downwardly and outwardly beveled edge as shown to provide for complete closure 75 (represented diagrammatically at 122^a) may be

thereof in the upper extreme position of valve member 83, and to provide for a gradual increase in the annular area of the opening upon downward movement of member 83.

Member 86 fits closely around the open lower end of a relatively short tube 88, and is secured to the latter as by means of a set screw 89. The reduced upper end 90 of tube 88 fits within an opening of corresponding size formed in a metal member 91; tube 88 being rigidly secured in position, as by means of a ring of solder, as indicated at 92. The bracket member 66 is also rigidly and permanently attached to member 91 by soldering or the like, as indicated at 93.

Member 91 is provided with a relatively large recess 94 and a flared neck or passage 95 leading therefrom to the aforementioned recess 19. The material surrounding neck 95 has an end portion fitted into a correspondingly shaped opening in member 16, and is soldered or otherwise secured thereto as shown at 96. An externally threaded nipple 97 penetrates an opening in the wall of recess 94 and is soldered or otherwise rigidly secured to said wall, as indicated at 98. Nipple 97 is provided with kerfs 99 and 100 extending downwardly throughout the major portion of the length thereof, and an internally threaded cap 101 is manually adjustable with respect thereto to provide for variation between zero and a predetermined maximum value the amount of air which may be drawn through nipple 97.

An injector nozzle 102 is positioned within recess 94, said nozzle being centrally aligned with respect to the tapered passage or neck 95, and the tip 103 of the nozzle being adjustably positioned at the desired point with respect to the entrance to passage 95. The means affording such adjustment of nozzle 102 comprises a threaded portion 104 thereon which takes into a tapped opening 105 in the reduced portion 106 of a hollow metal supporting member 107; said reduced portion 106 fitting into an opening provided in the walls of recess 94, and being soldered or otherwise rigidly attached thereto, as shown at 108. The hollow rear end portion 109 fits closely but rotatably and slidably within the rear end portion 110 of member 107; a part of portion 110 being reduced and externally threaded as shown to permit the same to penetrate an opening 111 provided in the angular wall portion 112 of housing 25. A pair of gaskets 113 and 114 is arranged on opposite sides of wall portion 112, and a suitable internally threaded metal cap 115 cooperatively engages the thread on reduced portion 110 to clampingly engage the gasket 114 and thus afford a gas-tight seal for the open rear end of nozzle 102. Member 107 is provided with a recess 116 surrounding a part of the length of portion 109 of the nozzle, the part thus surrounded preferably having a pair of transverse passages 117 and 118 drilled therethrough to afford communication between recess 116 and the longitudinal passage through the nozzle. The rear end of the nozzle is provided with a kerf 119 or other means to provide for removal of nozzle 102 for cleaning the same or substituting another jet therefor; the cap 115 being removed.

Member 107 is provided with a tapped opening 120 communicating with recess 116; a nipple 121 being threaded thereinto to provide a gas-tight connection for one end of a relatively small pipe or conduit 122 by which a gas sample is supplied to the injector nozzle 102. Any suitable means (represented diagrammatically at 122^a) may be

provided for insuring the desired pressure of the gas sample supplied through pipe 122.

As will be noted the lever 69 (Fig. 1) is provided with a second bearing member 123 similar to that shown at 75. The recess in the lower surface of member 123 is adapted to accommodate and engage the conical upper end 124 of a short rod 125 having attached thereto a nut 126 which is adapted to accommodate more or less of the tapped end 127 of a relatively longer rod 128, only a fragment of which is shown in Fig. 1. Another portion of rod 128 is shown in Fig. 4 as having its conical lower end 129 bearing in a member 130 carried by a lever 131 which is shown as pivoted at 132; a downwardly extending portion 133 of which lever is shown as provided with a pen 134 for effecting a graphic indication upon a movable recording chart 135. In the particular form shown, the chart 135 is adapted to simultaneously provide for recording of the instantaneous total heating value per unit volume of the gas sample, as by means of the pen 136 which may be operated by means well known in this art. Where both total heating value and interchangeability characteristics of the gas are to be recorded, it is to be understood that chart 135 will be specially calibrated to afford the proper record of interchangeability. The indicator 137 in Fig. 4 is adapted to micrometrically indicate the instantaneous total heating value of the gas in conjunction with the peripheral scale 138, which may have suitable heating value numerals (not shown) applied thereto.

The operation of the device shown in Figs. 1, 2 and 4 is as follows: Upon connection of conduit 122 to a source of supply of the gas at a constant pressure and upon ignition of the mixture of gas and primary air at the tip 13 of the burner, fixed combustion zones will result, depending upon the composition of the gas and adjustments of the equipment. When the mixture of gas and primary air is first ignited to provide the burner flame the various parts of the equipment, including the bulb or container 36 and the body of liquid 51, may be assumed to be at room temperature. The valve member 83 will then be at approximately its maximum lowered position, so that the amount of induced air will be at a maximum. With a gas composition such that the equipment is adjusted within the operating range, the percentage value of primary air will be high enough to produce a small inner cone flame, the tip 48 of probe 46 projecting a substantial distance into the primary combustion zone, or inner cone.

Heat from the primary combustion zone is therefore rapidly conducted through probe 46, rod 40 to hollow portion 41 of the latter, and from rod 40 to bulb or container 36, though the portion 39 of the latter. Portion 41 and container 36 transmit this heat to the liquid 51, raising the temperature of the liquid, and therefore increasing the vapor tension of the liquid in bulb 36. In addition to the heat transmitted to probe tip 48 by direct contact with said combustion zone of the inner cone of the flame, some heat is also transmitted by radiation from the flame to the associated parts.

As the temperature of the bulb 36 and the lower portion of probe 46 and rod 40 increases, the difference in temperature between the incoming relatively cool primary air-gas mixture and bulb 36 produces a cooling effect on said bulb, thus tending to counteract the temperature increase of the bulb. With the probe tip 48 projecting

5 into the combustion zone of the inner cone as aforementioned heat is transmitted to the bulb 36 and liquid 51 at a high rate of speed, as compared with the rate at which heat is removed from said bulb and liquid by the cooling effect of the primary air-gas mixture flowing upwardly therealong, so that the temperature and vapor tension of the liquid in the bulb will rise. The increase in vapor pressure in bulb 36 is transmitted through the liquid 51 in tube 27 to bellows element 52, thus extending or expanding the latter in opposition to the force of spring 71 and causing arm 69 to move in a counterclockwise direction with respect to the aforementioned point 15 of oscillation 65.

The accompanying partial closure or reduction in size of the area between valve member 83 and the periphery of valve opening 87 restricts the flow of primary air to the burner 11, thereby reducing the percentage of primary air in the gas-air mixture; thus lowering the ignition velocity of the mixture. Although this reduction in ignition velocity is accompanied by a decrease in total flow from the burner tip 13, this latter change is 20 small as compared with the change in ignition velocity, and therefore the inner combustion zone extends itself until the same has risen above the tip 48 of the probe. With the inner cone above the tip 48 of the probe only radiant heat can 25 reach the thermometer bulb, whereas the effect of this radiant heat is substantially neutralized by the cooling effect of the comparatively cool primary air-gas mixture flowing in contact with the bulb and probe.

30 The temperature of the liquid 51 in bulb 36 will therefore drop quite rapidly, the consequent reduction in vapor pressure of the liquid permitting lever 69 to move in a clockwise direction due to the force exerted by spring 71. The ignition 35 velocity is therefore increased until the inner cone (49) of the flame engages the tip of the probe, at which time the rate of heat transfer to the bulb increases rapidly. Sequential heating and cooling of the bulb incidental to engagement 40 and disengagement of the probe tip with the inner combustion zone establishes an average rate of heat transfer to the bulb at a value which will maintain valve member 83 in such a position that the inner cone 49 of the flame will just touch the 45 probe tip 48.

50 As will be apparent, there is a distinct and wide difference in temperature between points infinitesimal distances respectively below and above the inner combustion zone, and that therefore an infinitesimal change in height of the inner cone will result in an extremely large change in rate of heat transfer to the bulb and liquid 51, wherefore the actual temperature used to position valve member 83 and thus control the height 55 of inner cone 49 is of relatively slight importance. For example, if the force applied by spring 71 were doubled by adjusting the same or increasing its strength or caliber, so that the thermometer bulb 36 and liquid 51 would have to be at a very 60 much higher temperature, valve member 83 would nevertheless assume substantially the same position under the aforescribed conditions; because, although the inner cone would have to be at an infinitesimally lower average position, this 65 difference in height of the inner cone is insignificant in the practical measurement. Similarly, if gas compositions should differ, to cause a different positioning of valve 83 and therefore require a different bulb temperature, the average height of cone 49 would be established at the 70

same position. From the foregoing it is obvious that the relative position of valve member 83 and lever 69 supporting the same will indicate the degree of adjustment of the supply of primary air required to maintain the inner combustion zone 49 at a substantially constant position. Gases which produce the same positioning of lever 69 will therefore be interchangeable in respect of maintaining a predetermined height of the inner cone and insuring stability of the flame on burners of similar construction.

As aforeindicated, the calibration of the device may be changed when in use to accommodate various substantially different types of gases (as, for instance, changing from gases having high values of the factor K to gases having low values of the factor K) by proper adjustment of cap 101 to vary the amount of primary air supplied to a substantially fixed degree, and/or by substituting for member 86 a member having a valve opening which is either larger or smaller than the opening 87 aforedescribed.

In practice the housing 25 is provided with a front plate or cover (not shown) to substantially completely enclose the device, whereby the effect of drafts of ambient air upon the burner flame is minimized; said housing being also preferably provided in its upper end wall (not shown) with a pipe or conduit which serves as a flue for the combustion products released by the burner flame. It is to be understood, however, that the interior of housing 25 will have sufficient access to the surrounding air to insure the required amount of primary air and an adequate amount of secondary air for combustion with the gaseous mixture at the burner tip. In some installations, however, it may be desirable to seal off the housing 25 from the ambient air (the flue being suitably connected with a smoke-stack or the like for disposal of the combustion products); in which case a special supply of air will be fed by conduit to the housing to provide a sufficient quantity of primary and secondary combustion air. Such an arrangement is desirable where the ambient air may possibly be of combustible character.

In the modification illustrated in Fig. 3, the parts 13, 40 and 45 may be identical with the corresponding parts aforedescribed. In Fig. 3, however, the probe 137 is of special form, the same preferably being tapered somewhat and having a blunt or hemispherical tip 138 and a solid disk 139 concentric with and spaced downwardly a substantial distance from said tip. The primary effect of disk 139 is to substantially widen and flatten or blunt the upper end portion 140 of the inner cone 141 of flame 142. The redistribution of the inner cone in this manner is desirable with gases having a high value of K, where the inner cone would normally become large and therefore considerably elongated; thus rendering it difficult to provide the zones of distinctly different temperatures in proper operative relationship to the tip of the probe. Conversely, upon an increase in height of inner cone 141 with respect to probe 138, the combustion zone of said inner cone will be spaced a greater distance than normal from both the tip 138 and the periphery of disk 139. By this means the sensitivity of the device as a whole to variations in the interchangeability factor K of the test gas may be increased.

In Fig. 5 I have shown, slightly more diagrammatically, an adaptation of my invention to the distant indication and recordation of variations in the interchangeability characteristics,

or factor K, of a continuous test sample of gas. Thus whereas I have shown in Fig. 5 only that part of tubular portion 27 which communicates with bellows 52, it is to be understood that the upper part of tube 27 will be connected with the container 36 in the manner illustrated in Fig. 1, and that the various other parts of the burner may be the same as those shown in Fig. 1. The pointer 80a in Fig. 5 is substantially like that shown at 80 in Fig. 1; the cooperating scale 82 being the same in both figures. The parts 65a, 79a and 69a shown diagrammatically in Fig. 5 may correspond exactly with the parts 65, 79 and 69 in Fig. 1. The parts 83, 86, 87 and 125 in Fig. 5 are also preferably identical with the correspondingly designated parts in Fig. 1.

In Fig. 5, however, I have shown a follow-up lever 143 which is fixedly pivoted upon a pin 144, such point of pivotal support of lever 143 preferably being concentric with the center of oscillation of pointer arm 80a, as represented at 65a in Fig. 5 by the point of bending of cantilever spring 65 in Fig. 1. Lever 143 has attached to its upper end a jet 145, which is connected by a flexible conduit 146 with a conduit 147 to which air, for instance, is supplied through a fixed orifice 148 and a pressure regulator 149 from a suitable source of compressed air as represented by the arrow 150. Conduit 147 likewise communicates, through branch 151, with the interior of an expansible metal bellows 152, the rear end of which is rigidly attached to a fixed bracket 153 and the free end of which carries a stud 154 which continuously bears against the left-hand side of the lower end 155 of lever 143. A coiled compression spring 156 is interposed between the right-hand side of the lever end 155 and a second arm 157 of bracket 153.

The pointer 80a has attached thereto a flap or closure member 158 which is adapted for co-operation with the open end of jet 145, to effect closing of the latter or opening thereof to a variable degree (for bleeding of the air and reduction of pressure within conduit 147) according to the relative positions of pointer 80a and said follow-up lever 143.

Conduit 147 also communicates, through branch 159, with a Bourdon tube 160 which responds to variations of pressure within conduit 147; said Bourdon tube 160 having the usual indicating arm 161 which is adapted for co-operation with a suitable scale 162, which may have legends exactly corresponding with those employed on scale 82. The Bourdon tube 160 may thus act to afford a distant indication of the interchangeability characteristics of the gas, as indicated locally by the pointer 80a and scale 82.

Conduit 147 further communicates, through branch 163, with the interior of an expansible metal bellows 164, the rear end of which is attached to a bracket 165 attached to the wall of a recorder housing 166; the free end of bellows 164 having a stud 167 which continuously engages the left-hand side of the lower end 168 of a lever pivoted at 169; a coiled compression spring 170 being interposed between the right-hand side of lever end 168 and another wall of housing 166. The upper end 171 of said lever carries a pen or marker 172 which is adapted to cooperate with an automatically movable chart 173 to afford a continuous record 174 of the interchangeability characteristics of the test gas.

The operation of the pneumatic distant indicating and recording system shown in Fig. 5 is

as follows: As the pointer 80^a moves toward the right (or, in a clockwise direction) the amount of bleeding of air (entering through the supply regulator 149 and orifice 148) as jet 145 increases, thus reducing the pressure in the conduit 147 and its branches 151, 159, and 163. The spring 156, which biases follow-up lever 143 to move in a clockwise direction is opposed to the force applied to said lever by bellows 152, and said spring 156 has a relatively steep pressure characteristic. That is to say, the force of spring 156 increases rapidly as the follow-up lever 143 moves in a counterclockwise direction, whereby the same exerts a predetermined force in each different position of said lever. To position said follow-up lever it is therefore necessary that the fluid pressure within bellows 152 shall exert a force equal to the force of spring 156, so that for each position of said lever there will be a predetermined pressure in said bellows. This same fluid pressure is transmitted through the branch conduits to the recording meter 166 and the indicating gauge 160. The fluid pressure in the devices last mentioned is opposed by springs (the spring 170 in recorder 166 and the Bourdon tube in gauge 160) of equivalent or corresponding force, so that the movable element of said devices may assume definite or predetermined positions for each different pressure of the fluid.

The arrangement is such that jet 145 is completely closed when the flapper or plate 158 is against the tip of said jet. An extremely small amount of movement of flapper away from the jet allows air to flow from the jet, thus relieving the pressure in the system and causing the spring 156 to move the follow-up lever 143 in a clockwise direction to again tend to close off the flow from the jet. In this new position of lever 143 less fluid pressure will be required in the system to balance the spring 156, so that the distance between the jet and the flapper will be an infinitesimal amount greater than in the first instance, because an opening of infinitesimal size is sufficient to bleed off air at a rate which will reduce the pressure by an appreciable amount, to thereby establish the new pressure required to balance the spring 156. The pressure regulator 149 in the air supply to the system is preferably set to maintain a pressure slightly higher than the pressure required to move the follow-up lever to the end of the scale in the counterclockwise direction. With the jet 145 entirely closed off, this pressure will then be established in the system, and the recorder 166, gauge 160 and follow-up lever 143 will be in the sub-zero position.

With the aforescribed gas interchangeability determining device (Fig. 1) reading zero, air would then escape from the jet 145, causing the follow-up lever 143 to move up on the scale 82 (that is, toward the left) to a point where the leakage of the jet is reduced to a value which will establish the pressure required to balance the follow-up lever 143 and bring the jet substantially in contact with the flapper. As the indication of the gas interchangeability determining device increases and arm 80^a moves toward the right, performance is similar, the follow-up lever 143 following the movement of the arm 80^a, except that the gap between the jet 145 and flapper 158 increases slightly as the value of factor K (indicated by arm 80^a on scale 82) becomes higher. For all practical purposes the follow-up lever 143 maintains the same relative position as the arm

80^a. Inasmuch as the spring loading characteristics of the recorder 166, indicating gauge 160 and follow-up lever 143 are similar in respect of their scale readings, corresponding positions will be assumed by these devices, and distant indication and recording of the same value indicated locally by arm 80^a and scale 82 will be obtained.

I claim:

1. The method of measuring gas interchangeability in a device of the Bunsen burner type, which comprises normally subjecting a heat conducting thermometric probe to the temperature of the primary air-gas flow immediately ahead of the primary combustion zone as a measure of the height of the inner cone of the flame, whereby the probe is rendered extremely sensitive to variations in the height of said inner cone, effecting adjustment of the primary air flow to the burner as a function of the rate of transfer of heat to the probe in a manner to counteract variations in the height of said inner cone, and utilizing the setting of said primary air adjustment as an indication of a property of the gas definitely related to gas interchangeability.
2. The method of measuring the degree of interchangeability of a gas, which comprises supplying a continuous sample of said gas at a substantially constant pressure to a burner of the Bunsen type, utilizing said flow of gas to normally effect injection into said burner of a predetermined proportional flow of primary air for mixture with said gas, igniting said mixture of gas and primary air at the burner tip to provide a flame the inner cone of which is normally of predetermined height, positioning a heat conducting thermometric probe at the desired point of the combustion zone at the tip of said inner cone, said probe being thermally responsive to movement of said combustion zone above and below the upper end of the probe to generate a source of power of correspondingly variable value, utilizing the variable value of the generated power to effect variation of the proportionality of said flow of primary air, whereby said inner cone is maintained at substantially said predetermined height, and measuring and indicating the amount of variation in the proportionality of said flow of primary air so effected.
3. The method of measuring the degree of interchangeability of a gas, which comprises supplying a continuous sample of said gas at a substantially constant pressure to a burner of the Bunsen type, utilizing said flow of gas to normally effect injection into said burner of a predetermined proportional flow of primary air for mixture with said gas, igniting said mixture of gas and primary air at the burner tip to provide a flame the inner cone of which is normally of predetermined height, positioning a heat conducting thermometric probe at the desired point of the combustion zone at the tip of said inner cone, said probe being thermally responsive to movement of said combustion zone above and below the upper end of the probe as an incident to variations in the ignition velocity of said mixture of gas and primary air to generate a source of power of correspondingly variable value, utilizing the value of the generated power to effect variation of the proportionality of said flow of primary air, whereby said inner cone is maintained at substantially said predetermined height, measuring the amount of variation in the proportionality of said flow of primary air so effected, and utilizing said measurement as an indication

of the degree of interchangeability of said gas with respect to a gas of known combustion characteristics.

4. In combination, a Bunsen type burner, means for supplying gas at a constant pressure to the jet of the burner, means including an adjustable valve for controlling the induced flow of primary air to said burner, the mixture of gas and air being ignited in the presence of secondary air to provide a flame, a heat conducting probe arranged in a fixed position normally slightly below the tip of the inner cone of said flame so that the rate of heat transfer to the probe changes rapidly with a small increase or decrease in the height of said inner cone of the flame, means including an expansible medium associated with said probe and responsive to the heat conducted by the latter for effecting variation in the positioning of said adjustable valve, and means associated with said valve for indicating the degree of interchangeability of said gas with a gas of known combustion characteristics.

5. In combination, a Bunsen type burner, means including a jet for supplying thereto a continuous flow of gas at a predetermined constant pressure, means including an adjustable valve for permitting induction of primary air to said burner by the injector effect of said flow of gas, a thermometric probe positioned within the tube of said burner and projecting upwardly a substantial distance beyond the burner tip, the tip of said probe being located in line with and at the top of the inner cone of the burner flame in the normal condition of the latter, and said probe being thermally responsive to variations in the height of said inner cone to effect corresponding adjustments of said valve, whereby the height of said inner cone is maintained substantially constant.

6. In combination, a Bunsen type burner, means including a jet for supplying thereto a continuous flow of gas at a predetermined constant pressure, means including an adjustable valve for permitting induction of primary air to said burner by the injector effect of said flow of gas, a thermometric probe positioned within the tube of said burner and projecting upwardly a substantial distance beyond the burner tip, the tip of said probe being located in line with and at the top of the inner cone of the burner flame in the normal condition of the latter, said probe being thermally responsive to variations in the height of said inner cone to effect corresponding adjustments of said valve, whereby the rate of supply of primary air to said burner is varied, to thereby maintain substantially constant the height of said inner cone, and associated means movable with said valve to directly indicate the degree of interchangeability of said gas with respect to a gas of known combustion characteristics.

7. In combination, a burner of the Bunsen type, means including a jet for supplying thereto a continuous flow of gas at a predetermined constant pressure, means including an adjustable valve for permitting induction of primary air to said burner by the injector effect of said flow of gas, a thermometric probe positioned within the burner tube and projecting upwardly a substantial distance beyond the burner tip, the tip of said probe being located in line with and at the top of the inner cone of the burner flame in the normal condition of the latter, said probe having associated therewith a bellows system including a container located within the burner tube, a bel-

lows located exteriorly of said burner tube, a conduit affording communication between said container and said bellows, and a common body of vaporizable liquid substantially filling said container, said bellows and said conduit, whereby said liquid is thermally responsive to variations in the height of said inner cone to provide for corresponding degrees of expansion or contraction of said bellows, said bellows having a movable part thereof associated with said valve to provide for corresponding movements of the latter whereby the proportionality of the amount of primary air induced into said burner is varied, to thereby maintain substantially constant the ignition velocity of the mixture of gas and primary air and the height of said inner cone, a pointer movable with said valve, and a suitably calibrated scale associated with said pointer, whereby the degree of interchangeability of said gas with respect to a gas of known combustion characteristics is indicated.

8. In a device for measuring the degree of interchangeability of a gas with respect to another gas of known combustion characteristics, in combination, a Bunsen type burner, means including a nozzle for continuously supplying a flow of gas at a predetermined pressure to said burner, associated means for controlling the total amount of primary air induced into said burner by said flow of gas through said nozzle, said last mentioned means including a valve associated with said burner and having an element thereof spring-biased to a given position, a thermometer including a probe the upper end of which is located at the normal tip of the inner cone of the burner flame, and means associated with said probe and adapted to act against the spring-bias of said valve element to maintain the latter in a predetermined position so long as the inner cone of said flame is of a given normal height, the arrangement being such as to insure a predetermined rate of opening or closing movement of said valve element as an incident to an increase or decrease, respectively, in the height of said inner cone with respect to the normal height thereof.

9. In a device for measuring and indicating the degree of interchangeability of a gas with respect to another gas or gases of known combustion characteristics, in combination, a Bunsen type burner, means including a nozzle for continuously supplying a flow of gas at a predetermined pressure to said burner, associated means for controlling the total amount of primary air induced into said burner by said flow of gas through said nozzle, said last mentioned means including a valve associated with said burner and having an element thereof spring-biased to a given position, a thermometer including a probe the upper end of which is located at the normal tip of the inner cone of the burner flame, means associated with said probe and adapted to act against the spring-bias of said valve element to maintain the latter in a predetermined position so long as the inner cone of said flame is of a given normal height, the arrangement being such as to insure a predetermined rate of opening or closing movement of said valve element as an incident to an increase or decrease, respectively, in the height of said inner cone with respect to the normal height thereof, and means including a pointer movable with said valve element in one direction or the other, said pointer having a suitable scale associated therewith whereby the degree of interchangeability of said gas is indicated.

10. In a gas interchangeability measuring device, in combination, a Bunsen type burner, a thermometer including a probe the upper end of which is located at the normal tip of the inner cone of the burner flame, said thermometer also including a bellows system and a vaporizable liquid contained therein, means for supplying a continuous and substantially constant flow of gas to said burner, associated means for controlling the total amount of air induced into said burner by said flow of gas, said last mentioned means including a valve spring-biased to a given position, the pressure of vapor within said bellows system acting against the spring-bias of said valve to maintain the latter in a predetermined position so long as the inner cone of said flame is of a given normal height, and the arrangement being such as to insure a predetermined rate of decrease or increase in said vapor pressure as an incident to an increase or decrease, respectively, in the height of said inner cone with respect to said normal height thereof.

11. In a gas interchangeability measuring device, in combination, a Bunsen type burner, a thermometer including a probe the upper end of which is located at the tip of the inner cone of the burner flame, said thermometer also including a bellows system and a vaporizable liquid contained therein, means for supplying at a predetermined pressure a continuous flow of gas to said burner, associated means for controlling the total amount of air induced into said burner by said flow of gas, said last mentioned means including a valve spring-biased to a given position, the pressure of vapor within said bellows system acting against the spring-bias of said valve to maintain the latter in a predetermined position so long as the inner cone of said flame is of a given normal height, the arrangement being such as to insure a predetermined rate of decrease or increase in said vapor pressure as an incident to an increase or decrease, respectively, in the height of said inner cone with respect to said normal height thereof, and associated means for indicating the degree of movement of said valve in one direction or the other from said predetermined position thereof.

12. In a gas interchangeability measuring device, in combination, a Bunsen type burner, a thermometer including a probe the upper end of which is located at the tip of the inner cone of the burner flame, said thermometer also including a bellows system and a vaporizable liquid contained therein, means for supplying at a predetermined pressure a continuous flow of gas to said burner, associated means for controlling the total amount of air induced into said burner by said flow of gas, said last mentioned means including a valve spring-biased to a given position, the pressure of vapor within said bellows system acting against the spring-bias of said valve to maintain the latter in a predetermined position so long as the inner cone of said flame is of a given normal height, the arrangement being such as to insure a predetermined rate of decrease or increase in said vapor pressure as an incident to an increase or decrease, respectively, in the height of said inner cone with respect to said normal height thereof, and associated means for indicating the degree of movement of said valve in one direction or the other from said predetermined position thereof, said last mentioned means being calibrated to indicate the degree of departure of the combustion characteristics of said gas from

75 a value of perfect interchangeability with respect to a gas of known combustion characteristics.

13. In a gas interchangeability measuring device, in combination, a Bunsen type burner, means for supplying a continuous flow of gas thereto, means including a valve for normally providing a substantially constant flow of air for mixture with said gas, said mixture of gas and air when ignited at the burner tip being adapted to normally provide a flame having an inner cone of predetermined height, a probe supported by said burner and having its tip located adjacent the tip of said inner cone, means comprising a container including an expandable bellows, a quantity of vaporizable liquid within said container, an oscillatable support for said valve, said bellows being arranged on one side of said support to bias said valve in one direction and a spring for biasing said valve in the opposite direction, the quantity of heat transmitted from said inner cone to said probe being adapted to provide a balancing effect of said bellows against said spring whereby said valve is maintained in a predetermined position, the arrangement being such that the biasing effect of said bellows is decreased upon an increase in the height of said inner cone and increased upon a decrease in the height of said cone with respect to the normal height thereof, to thereby effect adjustments of said valve, and means associated with said valve to indicate the degree of adjustment thereof in either direction from its said predetermined position.

14. In a gas interchangeability measuring device, in combination, a Bunsen type burner, means for supplying a continuous flow of gas thereto, means including a valve for normally providing a substantially constant flow of air for mixture with said gas, said mixture of gas and air when ignited at the burner tip being adapted to normally provide a flame having an inner cone of predetermined height, a probe supported by said burner and having its tip located adjacent the tip of said inner cone, means comprising a container including an expandable bellows, a quantity of vaporizable liquid within said container, an oscillatable support for said valve, said bellows being arranged on one side of said support to bias said valve in one direction and a spring for biasing said valve in the opposite direction, the quantity of heat transmitted from said inner cone to said probe being adapted to provide a balancing effect of said bellows against said spring whereby said valve is maintained in a predetermined position, the arrangement being such that the biasing effect of said bellows is decreased upon an increase in the height of said inner cone and increased upon a decrease in the height of said cone with respect to the normal height thereof, to thereby effect adjustments of said valve, means associated with said valve to indicate the degree of adjustment thereof in either direction from its said predetermined position, and said last mentioned means being calibrated to indicate the degree of interchangeability of said gas with a gas of known combustion characteristics.

15. In a gas interchangeability measuring device, in combination, a Bunsen type burner, means for supplying a continuous flow of gas thereto, means including a valve for normally providing a substantially constant flow of air for mixture with said gas, said mixture of gas and air when ignited at the burner tip being adapted to normally provide a flame having an inner cone

of predetermined height, a probe supported by said burner and having its tip located adjacent the tip of said inner cone, means comprising a container including an expansible bellows, a quantity of vaporizable liquid within said container, an oscillatable support for said valve, said bellows being arranged on one side of said support to bias said valve in one direction and a spring for biasing said valve in the opposite direction, the quantity of heat transmitted from said inner cone to said probe and the rate of dissipation of heat from the latter and from the liquid within said container being such as to provide a balancing effect of said bellows against said spring whereby said valve is maintained in a predetermined position, the arrangement being such that the biasing effect of said bellows is decreased upon an increase in the height of said inner cone and increased upon a decrease in the height of said cone with respect to the normal height thereof, to thereby effect adjustments of said valve, means associated with said valve to indicate the degree of adjustment thereof in either direction from its said predetermined position, and said last mentioned means being calibrated to indicate the degree of interchangeability of said gas with a gas of known combustion characteristics.

16. In a gas interchangeability measuring device, in combination, a Bunsen type burner, means for supplying a continuous flow of gas thereto, means including a valve for normally providing a substantially constant flow of air for mixture with said gas, said mixture of gas and

air when ignited at the burner tip being adapted to normally provide a flame having an inner cone of predetermined height, a probe supported by said burner and having its tip located adjacent the tip of said inner cone, means comprising a container including an expansible bellows, a quantity of vaporizable liquid within said container, an oscillatable support for said valve, said support including a spring of the cantilever type, said spring providing a frictionless connection and insuring definite positioning of the valve with respect to its seat, said bellows being arranged on one side of said support to bias said valve in one direction and a spring for biasing said valve in the opposite direction, the quantity of heat transmitted from said inner cone to said probe and the rate of dissipation of heat from the latter and from the liquid within said container being such as to provide a balancing effect of said bellows against said spring whereby said valve is maintained in a predetermined position, the arrangement being such that the biasing effect of said bellows is decreased upon an increase in the height of said inner cone and increased upon a decrease in the height of said cone with respect to the normal height thereof, to thereby effect adjustments of said valve, means associated with said valve to indicate the degree of adjustment thereof in either direction from its said predetermined position, and said last mentioned means being calibrated to indicate the degree of interchangeability of said gas with a gas of known combustion characteristics.

EDWIN X. SCHMIDT.
